UNITED STATES PATENT OFFICE.

HENRY LANGE, OF QUINCY, ILLINOIS.

GAS BURNER FOR COAL OVENS.

1,425,985.

Specification of Letters Patent. Patented Aug. 15, 1922.

Application filed January 19, 1921. Serial No. 438,414.

To all whom it may concern:

Be it known that I, HENRY LANGE, a citizen of the United States, residing at Quincy, in the county of Adams and State 5 of Illinois, have invented certain new and useful Improvements in Gas Burners for Coal Ovens; and I do hereby declare the following to be a full, clear, and exact description of the invention, such as will enable others skilled in the art to which it 10 appertains to make and use the same.

The present invention relates generally to cook stoves or ranges using both coal and gas for fuel, and the invention appertains 15 more particularly to a gas burner for the stove oven, this invention being an improvement over the gas burner for coal ovens disclosed in my Patent No. 1,306,917, granted June 17, 1919.

20 It is the object of the invention, in addition to the objects specified in such patent, to provide a novel and improved gas burner construction for the bottom of the oven, for efficiently heating the interior of the oven 25 by gas, and also providing for the effective heating of practically the entire surface of the bottom of the oven from underneath when coal is used, so as to avoid irregular heating of such surface owing to the presence 30 of the burner, should a pan or other object be placed over the burner.

Another object is the improvement of the 35 burner construction as over the construction shown in said patent, whereby to simplify the device, and enable same to be manufactured at lower cost, as well as rendering the 40 construction of greater utility and advantage, and providing for the efficient and practically uniform heating of the burner portion of the oven bottom from underneath when coal is used as fuel.

With the foregoing and other objects in view, which will be apparent as the description proceeds, the invention resides in the 45 construction and arrangement of parts hereinafter described and claimed, it being understood that changes can be made within the scope of what is claimed without departing from the spirit of the invention.

50 The invention is illustrated in the accompanying drawings, wherein:—

Figure 1 is a front view of a coal stove or range, showing the oven door removed, and the gas burner in dotted lines.

55 Figs. 2 and 3 are enlarged vertical sections on the lines 2—2 and 3—3 of Fig. 4.

Fig. 4 is a plan view of the oven bottom showing the burner, a portion of the cover plate being broken away.

A conventional form of stove or range is 60 shown in the drawings, the same as in said patent, and has the usual oven 1 provided with the bottom 2 under which the flue 3 extends for the passage of the products of combustion around the oven and underneath 65 same to the outlet 4 leading to the outlet flue or pipe 5. In using gas for heating the oven, the back wall of the oven is provided with ventilating openings 6 near the top of the oven leading to the flue or pipe 5, thereby permitting the products of combustion from burner to pass off to the chimney. 70

In carrying out the invention, the oven bottom 2, which is preferably a cast plate, is provided with an opening 7 to accommodate 75 the burner, and the opening is circular, as shown, with a notch 9 at one side, and said bottom has a downwardly offset flange or step 8 along the edge of the opening. The bottom 2 is entirely open within the outline 80 of the opening 7 and flange or seat 8 in which the gas burner 16 is fitted, such burner being circular and of annular form to fit within the opening 7. The burner is hollow and has a lug 17' at one point to 85 enter the notch 9 and position the burner properly within the opening 7, and the burner has an inlet boss 17 underneath the lug 17' for the connection of a mixing tube or pipe 10, through which the gas flows 90 into the chamber of the burner. Such tube or pipe 10 extends underneath the oven 2 through one side wall of the stove and is provided at its outer end with an air mixer 11 and a controlling valve 12 connected to 95 the gas supply pipe 13.

The burner 16 has an annular marginal outstanding flange 36 flush with the top of the burner to seat on the flange 8, substantially flush with the oven bottom 2, and thereby support the burner removably on the bottom 2. This eliminates the recess or depression as disclosed in said patent for holding the burner and in which dirt or other foreign matter could accumulate, 100 thereby providing for a more sanitary construction. Thus, the margin of the burner has a close fit or joint with the oven bottom. The top 18 of the burner 16 slopes inwardly on a curve and is provided with the gas outlet apertures 19. 110

The burner 15 is provided therein with

the spider having a central boss or hub 14 with an opening therein, and the radial channeled arms 15. The bottoms of the arms 15 merge at their outer ends into an 5 annular web 30 projecting inwardly from the inner periphery of the burner, and such web 30 has upstanding flanges 31 at its inner edge between the arms 15 and merging at their ends into the side walls of said 10 arms, leaving openings 22 between the arms of the spider. The gas burner 16 and spider are thus cast integral.

A cover plate or disk 20 is seated on the spider and is fastened down by means of 15 screws 21 extending downwardly through the plate 20 and threadedly engaging two arms of the spider, or other securing means can be used. This plate 20 covers the openings 22 and also the central opening of the 20 boss 14 and channels of the arms 15. The plate 20 is substantially flush with or slightly above the surface of the oven bottom, and the plate 20 and top of the burner 16 provide practically an unbroken surface 25 with the oven bottom, with only a slight annular space between the edge of the plate and top of the burner, such burner being located between the edges of the plate 20 and bottom 2. The spider hub or boss 14 has an 30 upper annular groove 35 intersecting the channels of the arms 15 for the flow of air from one channel to the other. By the provision of the spider having the openings 22 extending to the plate 20, the products of 35 combustion, when coal is used as fuel, can pass upwardly within the spider to contact with the plate 20, thus keeping said plate heated, the same as the oven bottom 2, so that an object placed on the oven bottom 40 over the burner will be heated substantially uniformly throughout its area. Thus, even though the provision of the fresh air inlet under the burner is made the plate 20 will be heated when coal is used to avoid a cold 45 spot in the oven bottom within the oven burner. The plate 20 also acts as a baffle for the inflowing fresh air, deflecting the same to flow radially from the opening of the boss 14 through the channels of the 50 arms 15 to the burner, and in this connection the margin or edge portion of the plate 20 extends beyond the flanges 31 and overhangs the web 30 and inner portion of the burner 16, thus directing the air against and out 55 wardly across the top of the burner to the apertures 19 and providing for a perfect mixture of the air with the flames or jets. The plate 20 has depending arcuate flanges 23 near its edge, which overlap the flanges 31, and the ends of the flanges 23 are spaced 60 apart at the outer ends of the arms 15, to provide openings 32 registering with the channels of said arms through which the air can flow to the burner under said plate 20. 65 The plate 20 has a lug 33 underneath same

behind one flange 23 to enter a notch 34 in the corresponding flange 31 to properly position the plate 20 on the spider for the reception of the screws 21.

Fresh air is admitted by way of a vertical 70 air tube 24, within the flue 3 having a slip connection 25 with the boss 14 and having its lower end communicating through an opening 26 provided in the bottom 29 of the stove, with a similar slip connection between 75 the lower end of said tube 24 and the stove bottom. Fresh air can therefore flow upwardly from below through the tube 24 to pass through the channels of the arms 15 to the burner. The tube 24 is cast with a partition or baffle 27 extending rearwardly to the back of the stove to compel the products of combustion within the flue 3 to flow forwardly around the tube 24 before passing through the outlet 4, thus uniformly heating 80 the oven bottom throughout its area. The upper and lower edges of the partition 27 are shaped to fit the oven and stove bottoms, the upper edge being recessed, as at 85 28, to fit under the burner 16 and its spider. 90

With the present construction as illustrated and described, the oven can be heated effectively with either the use of coal or gas as fuel, and when coal is used, the plate 20 and burner 16 both being exposed to the 95 products of combustion underneath, will be heated so as to establish a more uniform radiating surface at the bottom of the oven throughout the burner portion. The burner 16 being unobstructed underneath, will be 100 heated quickly by the products of combustion, as well as the plate 20 which is exposed to such products of combustion through the openings 22 of the spider. The present construction also makes for simplicity and reduction in manufacturing cost. When the mixing tube or pipe 10 is 105 unscrewed from the burner, the burner and spider, together with the plate 20, can be readily removed from the opening 7 of the 110 oven bottom for purpose of cleaning, repairs or replacement. Said plate and burner when placed in the opening 7 close the same.

Having thus described the invention, what is claimed as new is:—

115

1. A stove having an oven and a flue under the bottom of the oven, said oven bottom having an opening, and a gas burner removably fitted in and closing said opening and constructed for the upward penetration of 120 heat through the burner from the products of combustion in said flue.

2. A stove having an oven and a flue under the bottom of the oven, said oven bottom having an opening, and a gas burner 125 removably fitted in and closing said opening and arranged substantially flush with the oven bottom throughout the area of the burner, said burner being constructed for the upward penetration of heat through the 130

burner from the products of combustion in said flue.

3. A stove having an oven and a flue under the bottom of the oven, said oven bottom having an opening and a downwardly-offset flange along the edge of said opening, and a gas burner removably seated on said flange in said opening, said burner being substantially flush with said bottom throughout the area of the burner and closing said opening, the burner being constructed for the upward penetration of heat therethrough from the products of combustion in said flue.

4. A stove having an oven and a flue under the bottom of the oven, said oven bottom having an opening, an annular gas burner in said opening at the edge thereof, and a cover plate within the burner, said burner and plate closing said opening and being removable from the opening as a unit, said burner and plate providing for the upward penetration of heat therethrough from the products of combustion in said flue.

5. A stove having an oven and a flue under the bottom of the oven, said oven bottom having an opening, an annular burner in said opening at the edge thereof and having means within the same for the flow of air to the burner, and a cover plate over said means, said burner and plate closing said opening and being removable as a unit from said opening, said burner and plate providing for the upward penetration of heat therethrough from the products of combustion in said flue.

6. A stove having an oven and a flue under the oven, the oven bottom having an opening, an annular burner in said opening at the edge thereof having a spider therein provided with means for the flow of air to the burner, and a cover plate secured on said spider, said burner and plate being removable as a unit from said opening, and the openings of the spider exposing said plate to the products of combustion in said flue, said burner being directly exposed to the products of combustion in said flue, and the burner and plate closing said opening.

7. A stove having an oven and a flue under the bottom of the oven, the oven bottom having an opening, a cover plate over said opening, and a gas burner between the edges of said opening and plate, said burner and plate closing said opening and being removable as a unit from the opening, said burner and plate being exposed to the products of combustion in said flue for the upward penetration of heat through said burner and plate.

60 8. A stove having an oven and a flue under the bottom of the oven, the oven bottom having an opening and a downwardly-offset flange along the edge of the opening, an annular burner having a portion at its outer periphery seated removably on said

flange substantially flush with the oven bottom, said burner having a spider with its arms united with the inner periphery of said burner, said spider having means for the flow of air to the burner, and a cover plate secured on the spider substantially flush with the oven bottom, said plate being exposed through the openings of the spider to the products of combustion in said flue, and the burner being exposed directly to the products of combustion in said flue.

9. A stove having an oven and a flue under the bottom of the oven, said oven bottom having an opening, an annular gas burner to be disposed in said opening and exposed to the products of combustion in said flue, said burner having an integral spider therein and the spider being formed with channels for the flow of air to the burner, and a cover plate on the spider over the openings thereof and exposed to the products of combustion in said flue through said openings, said burner and plate closing said opening and being removable therefrom as a unit.

10. A stove having an oven and a flue under the bottom of the oven, the oven bottom having an opening, an annular gas burner to be disposed in said opening having an annular web along its inner periphery and an integral spider within the burner having the outer ends of its arms merging into said web, said spider having channels for the flow of air to the burner, said burner being exposed to the products of combustion in said flue, and a cover plate on the spider over the openings thereof and exposed through said openings to the products of combustion in said flue, said burner and plate closing said opening in the oven bottom and being removable from said opening as a unit.

11. A stove having an oven and a flue under the bottom of the oven, the oven bottom having an opening, an annular gas burner to be disposed in said opening having integral means therein for the flow of air from the center radially to the burner, and a cover plate over said means, said burner and plate closing said opening and being removable from said opening as a unit, said burner and plate being exposed to the products of combustion in said flue.

12. A stove having an oven and a flue under the bottom of the oven, said oven bottom having an opening, an annular burner to be disposed in said opening having a flange at its outer periphery to seat on the oven bottom around said opening, said burner having an annular web at its inner periphery, a spider within the burner integral therewith having a central opening and channeled arms merging at their outer ends into said web, and a cover plate on said spider over the channels of said arms,

said burner and plate being removable from said opening as a unit and being adapted to close said opening, the burner and plate being exposed to the products of combustion 5 in said flue.

13. A stove having an oven and a flue under the bottom of the oven, the oven bottom having an opening, an annular burner to be disposed in said opening having a 10 flange at its outer periphery to seat on the oven bottom around said opening, said burner having an annular web at its inner periphery, a spider within the burner integral therewith having a central opening and 15 channeled arms merging at their outer ends

into said web, and a cover plate on said spider over the channels of said arms, said web and plate having overlapping flanges between said arms, said burner and plate closing said opening and being removable 20 therefrom as a unit, and said burner and plate being exposed to the products of combustion in said flue.

In testimony whereof I have signed my name to this specification in the presence of 25 two subscribing witnesses.

HENRY LANGE.
